COAL MINING APPARATUS

Nils D. Levin and Ernst Feodor Muller, Columbus, Ohio, assignors to The Jeffrey Manufacturing Company, Columbus, Ohio, a corporation of Ohio

Application October 18, 1929, Serial No. 400,665

38 Claims. (Cl. 262—28)

The present invention relates to mining machines of the type comprising, generally, a truck movable over suitable trackways, a turn-table on the truck and a kerf cutter supported from the turn-table and vertically translatable relative thereto.

The invention has to do particularly with mechanism for driving the kerf cutter and for adjusting it to the desired operating planes.

10 In the accompanying drawings, we have shown an illustrative embodiment of our invention, and without further discussion of the general aspects of the invention, we shall proceed to describe it with reference to the drawings, wherein:

15 Figure 1 is a plan view of the complete machine. Figure 2 is a side elevation.

Figure 3 is an enlarged plan view with parts removed to reveal others.

Figure 4 is a vertical section through the cutter driving and adjusting mechanism.

Figure 5 is a section on line 5—5 of Figure 4.

Figure 6 is an enlarged plan view of a clutch included in the cutter driving train, and

Figure 7 is an axial section of the clutch of 25 Figure 6.

Referring to the drawings, the mining machine truck is designated by the reference numeral 100 and has mounted thereon a turn-table 101 which is supported, through the intermediary of an 30 annular supporting frame 101', on three pedestals 102, 103 and 104. A motor 105 mounted on the truck through suitable mechanism is adapted to drive a cable reel 106, the truck wheels, and through vertical screws disposed in pedestals 102, 35 103 and 104, is adapted to raise and lower the turn-table 101, proper differential actuation of the screws being effective to tilt the turntable as desired.

Disposed on the turn-table is a winding drum 40 107 which through a cable 108 anchored to an element fixed on the truck is adapted to swing the turn-table in either direction depending on the direction in which the cable is trained around the turntable and upon the direction of drum 45 rotation. Thus, the mining machine embodies self-contained means for propelling it over the mine tracks to move it from one part of the mine to the other, or to operatively engage its cutting instrumentality in a coal face, and also self-contained power means to elevate and swing its 50 turn-table.

Fixed on turn-table 101 is a projecting arm 1 having a number of longitudinally extending slots 4 through which it is adjustably secured to the 55 turn-table by means of bolts and nuts 3. A cap

screw 5 engaged in a nut 6 fixed in a vertical flange of the arm 1 engages with its head the rim of the turn-table and forms an adjustable abutment to limit positively, movement of the arm inwardly of the turn-table. It will also be 60 evident that upon loosening bolts and nuts 3 the cap screw may be adjusted to displace the arm away from the turntable or to permit movement of the arm toward the turntable. Depending from the projecting end of the arm 1 is a tubular portion or bearing 7. Also depending from the arm inwardly of bearing 7 is a guide frame 8 having opposed parallel guide grooves 9. Between the flanges 40 and 41 of these grooves, Figure 5, are engaged flanges 42 of a vertically adjustable bearing frame 10. A cutter bar support 11 has a circular flange 43 journalled in a bearing ring 44 of frame 10. The bearing ring rests on a shoulder of the flange and is retained thereon by means of an annulus 44'.

In a vertical bearing sleeve 12 formed in the turn-table to the rear of arm 1 and intersecting the axial line of the latter, is journalled a drive shaft 13 having fixed thereto a bevelled gear 14 engaging a pinion 15 fixed on the armature shaft 16 of a reversible electric motor 17 which is mounted on turntable 101 to project therebelow, Figure 3. Suitable control means for the motor are provided, but since such means are well understood, their illustration has not been thought 85 necessary. A sprocket wheel 18 is loose on the upper end of shaft 13 but is adapted to be engaged therewith by means of a clutch generally indicated at 19. In view of the restricted spaces in which the machine is required to operate, a special clutch of compact form has been provided and will be described in detail hereinafter. At its lower end shaft 13 has fixed thereto an eccentric 13' which, through a strap 13'' is adapted to 90 drive drum 107 through mechanism, as shown 95 for example in the copending application of Nils D. Levin, Serial No. 296,990, filed August 2, 1928.

A sprocket chain 20 connects sprocket 18 with a sprocket 21 stepped on the upper edge of bearing 7. Sprocket 21 has an upwardly extending 100 boss 21' journalled in a bearing 23 formed in a plate 24 fixed to arm 1, the bearing being coaxial with bearing 7. Sprocket 21 is also integral with a sleeve 22 depending in bearing 7 in spaced relation to the inner walls of the latter. Sleeve 22 105 is interiorly and longitudinally fluted to form a spline connection with the externally fluted head of a sleeve 25, sleeves 22 and 25 forming a hollow torque shaft adjustable as to length for driving cutter sprocket 26 which is secured to the lower 110

end of sleeve 25. Sprocket 26 engages a chain 27 having lugs 28 which carry bits 29, chain 27 traveling in suitable guides of an elongated horizontal cutter frame 109 in the well known manner.

5 The cutter support 11 has a head 30 stepped on sprocket 26. Head 30 has a spider integral therewith which supports guide flange 43 already described, and concentric with and spaced from the latter, an upwardly extending sleeve 31 surrounding sleeve 22 within bearing 7, a bushing 33 being interposed between it and the sleeve.

Sleeve 25 is interiorly threaded at its upper end to form a nut 34 engaged by a screw 35 which latter at its upper end has a radially expanded 15 integral flange 36 supported on the boss or crown of sprocket 21 through the intermediary of a bushing 36'. Flange 36 is preferably recessed so as to form shoulders 37 adapted to be engaged by the end 38 of a bolt 39 slidable on plate 24.

20 The weight of the cutter bar is supported by flange 36 through screw 35 and sleeve 25 and since the flange rests on the crown of sprocket 21 it will normally rotate with the latter. Under these conditions since nut 34 likewise rotates with the 25 sprocket, there will be no relative rotary movement of the screw and nut and the elevation of the kerf cutter will be unaffected. If, however, the end 38 of bolt 39 is moved to engage a shoulder 37 of flange 36, screw 35 will be arrested and will 30 no longer rotate with sprocket 21. Since nut 34 must rotate with sprocket 21 however, it will be moved along the screw so as to adjust the cutter bar vertically. The direction of movement of the nut longitudinally of the screw will, of course, 35 depend on the direction of rotation of sprocket 21, such direction, of course, being determined by the direction of rotation of armature shaft 16.

A boss 45 is formed on bearing frame 10 and has a vertical bore in which is vertically movable 40 a bolt 46.

A number of arcuately arranged apertures 47 in support 11 are adapted to be selectively engaged by bolt 46 to lock the kerf cutter in the desired position of angular adjustment relative to 45 frame 10. Frame 10, it will be remembered, is secured against rotation about shaft 25 through its engagement with guide 8.

The upper end of bolt 46 is circumferentially recessed as at 48 and is engaged by a yoke 49 fixed 50 on a shaft 50 which is journaled in bearings 51 on support 11 in a transverse position relative to arm 1. A lever 52 is fixed to each end of shaft 50 and a torsion spring 53 constantly urges the latter in such a direction as to hold bolt 46 in engagement with the selected aperture 47.

It will thus be evident that kerf cutter 109 is horizontally movable with the truck and is vertically and angularly movable relative to the truck due to its connection with the turn-table. Further, the cutter bar is vertically adjustable relative to the turn-table and may be secured in various angular positions relative to its axis which is defined by the torque shaft 22, 25.

Bolt 39 is slidable between plate 24 and cover plate 54 and is guided by blocks 55 and 56. The bolt is provided with a longitudinal slot 58 in which is disposed compression spring 57. At one end the spring abuts a lug 59 fixed to plate 24 and at its other end the end wall of slot 58, thus tending to urge the bolt away from flange 36 and out of the path of shoulders 37. A lever 60 is mounted upon a pin 61 at the end of bolt 39 remote from flange 36 in such a manner that swinging of the lever in either direction will engage one of its lugs 62 with a face 63 of the bolt

to move the latter into the path of shoulders 37. Since the spring 57 tends to release the bolt, the operator must hold the lever 60 if it is to be engaged to cause vertical adjustment of the kerf cutter.

It would be merely a matter of conjecture for the operator to stop the elevating mechanism at its limits, and to prevent serious results from overrunning of the mechanism, automatically acting stop devices are provided.

Bolt 39 is provided with an arm 65 to which is attached one end of a chain 64. At a distance from its point of attachment, the chain is passed through an aperture in plate 24 and its lower end connected to a vertical bolt 66 yieldingly anchored in frame 10. The length of the chain is so chosen that when the cutter bar approaches its lower limit of movement, the chain is tensioned, thereby retracting bolt 39 and interrupting the cutter bar movement.

At its side opposite arm 65, bolt 39 is provided with a shoulder 69 engaged by a lever 68 fixed on a vertical shaft 67 journalled for rocking movements. At its lower end, shaft 67 is provided with an arm 70 projecting in the opposite direction from lever 68 and provided at its distal end with a transversely extending boss in which is disposed a plunger 72 projected under the force of a compression spring 71. The end of plunger 72 is positioned in the path of a cam 73 formed on frame 10. Plunger 72 forms in effect a cam follower engaged by cam 73 at the upper limit of travel of the cutter bar to rock shaft 67 in a direction to retract bolt 39.

Due to the described mechanism, the bolt will 110 be released and lever 60 returned to neutral position at both limits of the vertical adjustment of the cutter bar. If the cutter bar is moving up, for example, and cam 73 abuts plunger 72, shaft 67 will be rocked and the bolt 39 withdrawn without material compression of spring 71. If now it is desired to move the cutter bar downwardly, the motor will be reversed and lever 60 moved to engage the bolt, thus rocking shaft 67 and further compressing spring 71, plunger 72, of course, being still in engagement with cam 73. Bolt or plunger 66 is similarly resiliently seated to permit the reengagement of bolt 39 when it is desired to move the cutter bar up from its lower limit position.

Referring now to Figs. 6 and 7, it will be noted the upper end of shaft 13 is radially flanged and provided with teeth as at 80. Sprocket 18 is provided with a crown toothed as at 81 in the same manner as the flange. A collar 82 is interiorly toothed as at 83, its teeth being adapted to fit between registering teeth 80 and 81 to lock the shaft and sprocket together.

Shaft 13 is provided at its upper end with a threaded radial bore in which engages a screw 84 provided with an annular shoulder 85. A plate 86 secured to collar 82 has a central aperture through which the upper end of screw 84 passes, the lower margins of the aperture resting on shoulder 85. Above plate 86 a flat handle or hand wheel 87 is secured to the stem of the screw. A spring 88 interposed between hand wheel 87 and plate 86 serves to prevent accidental relative movement of the hand wheel to the plate. Screw 84 is axially bored at its top and fitted with a lubricant receiving device 89.

It will be seen that by rotation of hand wheel 87 in a direction to displace screw 84 upwardly relative to shaft 13, the teeth 83 of collar 82 may be withdrawn from engagement with teeth 81 of

the sprocket so that rotation of shaft 13 will not be imparted to the latter. Movement of the screw in the opposite direction will reengage teeth 83 and 81 when the latter come into register 5 with teeth 80. The described clutch is extremely compact and is thus peculiarly adapted for use in the described connection. Low ceilings encountered in mines would make the use of an ordinary clutch impossible.

10 It will be understood that while we have necessarily described a particular embodiment of our invention, we do not limit ourselves except as determined in the following claims.

We claim:

15 1. In a machine of the class described, movable supporting means, a kerf cutter adjustable relative to said supporting means, a motor on said supporting means, a hollow torque shaft adjustable as to length operative between said motor and said cutter, said shaft comprising a pair of 20 telescoping portions, a screw concentric with said portions, and engaging a nut fixed to one of said portions, and means securing said screw against longitudinal movement relative to the other of 25 said portions, said screw and nut rotating with said shaft and holding said shaft and therewith said cutter in adjusted position.

2. In a machine of the class described, movable supporting means, a kerf cutter adjustable relative to said supporting means, a motor on said supporting means, a hollow torque shaft adjustable as to length operative between said motor and said cutter, said shaft comprising a pair of telescoping portions, a screw concentric with said portions and engaging a nut fixed to one of said 30 portions, means securing said screw against longitudinal movement relative to the other of said portions, said screw and nut rotating with said shaft and holding said shaft and therewith said cutter in adjusted position, and means for restraining said screw against rotation while the nut revolves to adjust said shaft and therewith the cutter.

3. In a machine of the class described, movable supporting means including an elevated horizontally projecting portion, an elongated vertically translatable horizontal kerf cutter beneath said portion, a motor on said supporting means, a vertical telescoping hollow torque shaft between said motor and said cutter, said shaft being journaled at its upper end in said projecting portion and at its lower end supporting said cutter, and means within said torque shaft supported by said projecting portion for supporting and adjusting the lower portion of said shaft and therewith the cutter.

4. In a machine of the class described, movable supporting means including an elevated horizontally projecting portion, an elongated vertically translatable horizontal kerf cutter beneath said portion, a motor on said supporting means, a vertical hollow torque shaft comprising a pair of telescoping sections, a bearing in said projecting portion for rotatably supporting the upper section, a bearing on the lower section for supporting the cutter, a screw suspended in said upper section and rotatable therewith, and a nut fixed to said lower section and engaging said screw.

5. In a machine of the class described, movable supporting means including an elevated horizontally projecting portion, an elongated vertically translatable horizontal kerf cutter beneath said portion, a motor on said supporting means, a vertical hollow torque shaft comprising a pair of telescoping sections, a bearing in said project-

ing portion for rotatably supporting the upper section, a bearing on the lower section for supporting the cutter, a screw suspended in said upper section and rotatable therewith, a nut fixed to said lower section and engaging said screw, and means for restraining the rotation of said screw while the nut is rotating.

6. In a machine of the class described, supporting means, a kerf cutter, and adjustable means between the two for supporting and driving the kerf cutter, said means comprising a hollow vertical torque shaft comprising telescoping upper and lower sections, a screw within the upper section, a flange on the upper end of the screw overlying and resting upon the top edge of the upper section, and a nut fixed to the lower section and engaging the screw.

7. In a machine of the class described, supporting means, a kerf cutter, and adjustable means between the two for supporting and driving the kerf cutter, said means comprising a hollow vertical torque shaft comprising telescoping upper and lower sections, a screw within the upper section, a flange on the upper end of the screw overlying and resting upon the top edge of the upper section, a nut fixed to the lower section and engaging the screw, and means on the supporting means for engaging said flange to lock the screw against rotation with said shaft.

8. In a machine of the class described, movable supporting means including a horizontally projecting portion provided with a vertical bearing aperture, a sleeve concentric with said aperture, a flange on said sleeve overlying and supported upon the top margins of said aperture, a second sleeve splined within the first and projecting therebelow, a screw suspended within the first sleeve, a nut fixed to the second sleeve and engaged by said screw, a flange provided on the lower end of the second sleeve, a kerf cutter mounting member surrounding the lower end of said second sleeve and supported by its flange, and means for inducing relative rotation of the screw and nut for vertically adjusting said mounting member.

9. In a machine of the class described, movable supporting means including a horizontally projecting portion provided with a vertical bearing aperture, a sleeve concentric with said aperture, a flange on said sleeve overlying and supported upon the top margins of said aperture, a second sleeve splined within the first and projecting therebelow, a screw suspended within the first sleeve, a nut fixed to the second sleeve and engaged by said screw, a flange provided on the lower end of the second sleeve, a kerf cutter mounting member surrounding the lower end of said second sleeve and supported by its flange, a guide sleeve on said mounting member projecting within said aperture and surrounding the lower end of the first named sleeve, and means for inducing relative rotation of the screw and nut for vertically adjusting said mounting member.

10. In a machine of the class described, movable supporting means including a horizontally projecting portion provided with a vertical bearing aperture, a sleeve concentric with said aperture, a flange on said sleeve overlying and supported upon the top margins of said aperture, a second sleeve splined within the first and projecting therebelow, a screw suspended within the first sleeve, a nut fixed to the second sleeve and engaged by said screw, a flange provided on the lower end of the second sleeve, a kerf cutter

- mounting member surrounding the lower end of said second sleeve and supported by its flange, a guide sleeve on said mounting member projecting within said aperture and surrounding the lower end of the first named sleeve, guide means depending from said projecting portion, means in connection with said mounting member and slidably engaging said guide means, and means for inducing relative rotation of the screw and nut for vertically adjusting said mounting member. 5
11. In a machine of the class described, movable supporting means including a horizontally projecting portion provided with a vertical bearing aperture, a sleeve concentric with said aperture, a flange on said sleeve overlying and supported upon the top margins of said aperture, a second sleeve splined within the first and projecting therebelow, a screw suspended within the first sleeve, a nut fixed to the second sleeve and engaged by said screw, a flange provided on the lower end of the second sleeve, a kerf cutter mounting member surrounding the lower end of said second sleeve and supported by its flange, means for securing said mounting member against rotation, and means for inducing relative rotation of the screw and nut for vertically adjusting said mounting member. 10
12. In a machine of the class described, movable supporting means including a horizontally projecting portion provided with a vertical bearing aperture, a sleeve concentric with said aperture, a flange on said sleeve overlying and supported upon the top margins of said aperture, a second sleeve splined within the first and projecting therebelow, a screw suspended within the first sleeve, a nut fixed to the second sleeve and engaged by said screw, a flange provided on the lower end of the second sleeve, a kerf cutter mounting member surrounding the lower end of said second sleeve and supported by its flange, a bearing member in which said mounting member is rotatable, means securing said bearing member against rotation, means for locking said mounting member to said bearing member in different angular positions, and means for inducing relative rotation of the screw and nut for vertically adjusting said mounting member. 15
13. In a machine of the class described, movable supporting means including a horizontally projecting portion, a kerf cutter beneath said portion, means for vertically translating said cutter relative to said portion, said translating means including a rotary member non-rotational during cutter translation, a locking element for said rotary member, and cam and lever mechanism automatically actuated at the upper limit of movement of the cutter to disengage said locking element from said rotary member and thereby arrest the cutter movement. 20
14. In a machine of the class described, movable supporting means including a horizontally projecting portion, a kerf cutter beneath said portion, means for vertically translating said cutter relative to said portion, said translating means including a rotary member non-rotational during cutter translation, a locking element for said rotary member, and means tensioned at the lower limit of movement of the cutter to automatically disengage said locking element from said rotary member and thereby arrest the cutter movement. 25
15. In a machine of the class described, movable supporting means including a horizontally projecting portion, a kerf cutter beneath said portion, means for vertically translating said cutter relative to said portion, said translating means including a rotary member non-rotational during cutter translation, a locking element for said rotary member, and means automatically actuated at the upper and lower limits of movement of the cutter to disengage said locking element from said rotary member and thereby arrest the cutter movement. 30
16. In a machine of the class described, a supporting frame, a kerf cutter adjustable relative to said frame, a motor on said frame, a torque shaft adjustable as to length operative between said motor and said cutter, a guide bearing supported from said frame concentric to and surrounding a portion of said shaft, and a guide bearing concentric to and surrounding another portion of said shaft and adjustable with said shaft. 35
17. In a machine of the class described, a supporting frame, a kerf cutter adjustable relative to said frame, a motor on said frame, a torque shaft adjustable as to length operative between said motor and said cutter, a guide bearing supported from said frame concentric to and surrounding a portion of said shaft, a guide bearing concentric to and surrounding another portion of said shaft and adjustable with said shaft, said guide bearings being in telescoping relation to each other. 40
18. In a machine of the class described, a supporting frame, a kerf cutter adjustable relative to said frame, a motor on said frame, a telescoping torque shaft between said motor and said cutter, and telescoping non-rotating housing elements for said shaft. 45
19. In a machine of the class described, a supporting frame, a kerf cutter adjustable relative to said frame, a motor on said frame, a telescoping torque shaft between said motor and said cutter, telescoping non-rotating housing elements for said shaft, and common means for telescoping the shaft and the housing elements for adjusting the kerf cutter. 50
20. In a mining machine, a supporting frame, a kerf cutter adjustable relative to said frame, a motor on said frame, a torque shaft between the motor and cutter and comprising telescoping tubular elements, and means for adjusting said shaft comprising a screw concentric therewith in threaded engagement with one of the tubular elements and having a thrust engagement with another of said tubular elements. 55
21. In a machine of the class described, a supporting frame, an arm projecting horizontally from said frame, a sleeve fixed to and depending from the free end of said arm, a second sleeve telescopically engaged with the lower portion of the first, a kerf cutter having a rotary drive element at the bottom of said second sleeve and coaxial therewith, means preventing rotation of said second sleeve, a motor on said frame, driving connections between said motor and said rotary element including a longitudinally extensible and collapsible torque shaft within said sleeves, and means for adjusting the kerf cutter toward and away from the frame. 60
22. In a machine of the class described, a supporting frame, an arm projecting horizontally from said frame, a sleeve fixed to and depending from the free end of said arm, a second sleeve telescopically engaged with the lower portion of the first, a kerf cutter having a rotary drive element at the bottom of said second sleeve and coaxial therewith, means preventing rotation of said second sleeve, a motor on said frame, driving connections between said motor and said rotary element including a longitudinally extensible and collapsible torque shaft within said sleeves, and means for adjusting the kerf cutter toward and away from the frame. 65
23. In a machine of the class described, a supporting frame, an arm projecting horizontally from said frame, a sleeve fixed to and depending from the free end of said arm, a second sleeve telescopically engaged with the lower portion of the first, a kerf cutter having a rotary drive element at the bottom of said second sleeve and coaxial therewith, means preventing rotation of said second sleeve, a motor on said frame, driving connections between said motor and said rotary element including a longitudinally extensible and collapsible torque shaft within said sleeves, and means for adjusting the kerf cutter toward and away from the frame. 70
24. In a machine of the class described, a supporting frame, an arm projecting horizontally from said frame, a sleeve fixed to and depending from the free end of said arm, a second sleeve telescopically engaged with the lower portion of the first, a kerf cutter having a rotary drive element at the bottom of said second sleeve and coaxial therewith, means preventing rotation of said second sleeve, a motor on said frame, driving connections between said motor and said rotary element including a longitudinally extensible and collapsible torque shaft within said sleeves, and means for adjusting the kerf cutter toward and away from the frame. 75

- said second sleeve, a motor on said frame, driving connections between said motor and said rotary element including a longitudinally extensible and collapsible hollow torque shaft with- 5 in said sleeves, and means for adjusting the kerf cutter toward and away from the frame, said last named means including a screw extending longitudinally of and within said hollow torque shaft. 23. In a mining machine, the combination with 10 a supporting frame, of a kerf-cutter comprising a cutter frame, means for driving said kerf-cutter comprising an extensible shaft mounted between said supporting frame and said kerf-cutter, an extensible enclosure for said shaft between said 15 frames, and guiding mechanism between said frames adapted to prevent swinging movement of said cutter frame on the axis of said shaft. 24. In a mining machine, the combination with 20 a support, of a kerf-cutter adjustable relatively thereto, an extensible hollow torque shaft connected to said kerf-cutter, said shaft comprising a pair of telescoping portions, a screw concentric to said shaft, a nut fixed to one of said portions, and means securing said screw against longitudinal movement relative to the other of said 25 portions. 25. In a mining machine, the combination with 30 supporting means, of a kerf-cutter, and means between said supporting means and said kerf-cutter for adjusting the position of the latter, said means comprising telescoping sections, a screw within one section, a flange on one end of the screw and resting against one end of said section, and a nut fixed to the other section and 35 engaging said screw. 26. In a mining machine, the combination with 40 supporting means, of a kerf-cutter, and adjustable means between said supporting means and said kerf-cutter for positioning the latter and driving the same, said means comprising a torque shaft having telescoping sections, a screw within one section, a flange on one end of said screw resting upon one end of said section, and a nut fixed to the other section and meshing with said 45 screw. 27. In a machine of the class described, a base member, a turntable rotatable on said base member, an arm projecting from said turntable in perpendicular relation to the axis of rotation of 50 the turntable, said arm having a portion overlying the turntable and provided with a plurality of longitudinally extending slots, clamping means extending through said slots in connection with the turntable, the arm being longitudinally displaceable relative to the turntable upon loosening said clamping means, said arm having a perpendicular flange extending in front of the turntable edge, and screw means mounted in said flange in substantially perpendicular relation thereto and abutting the turntable edge, said screw means serving as thrust transmitting means and being adjustable to effect longitudinal displacement of the arm relative to the turntable. 60 28. In a machine of the class described, the combination with a supporting frame, of a kerf cutter bodily adjustable relative thereto, an extensible torque shaft comprising telescoping sections for driving said kerf cutter in all of its adjusted positions, driving means for the torque 65 shaft, a screw and nut for adjusting the kerf cutter relative to said frame, and means for effecting relative rotation of the screw and nut, the screw being housed within the torque shaft, but being extrinsic to the torque action of the 70 torque shaft. 29. In a machine of the class described, the combination with a supporting frame, of a kerf cutter bodily adjustable relative thereto, an extensible torque shaft comprising telescoping sections for driving said kerf cutter in all of its adjusted positions, driving means for the torque shaft, a screw and nut for adjusting the kerf cutter relative to said frame, and means for rotating the nut relative to the screw, the screw being housed within the torque shaft, but being extrinsic to the torque action of the torque shaft. 80 30. In a mining machine, a support including a horizontally projecting arm, a downwardly extending tubular projection adjacent the free end of the arm, means defining a vertical guideway extending downwardly from the arm behind the tubular projection, a frame below the tubular projection and engaged in said guideway for vertical adjustment therealong, the guideway holding the frame against rotation about a vertical axis, a tubular member telescoped in said projection and having its lower end journaled in said frame, a cutter bar in connection with the lower end of said tubular member and rotatable therewith, means for connecting the cutter bar and frame to hold the cutter bar against movement about the axis of said tubular member, and means for driving the cutter bar, and means for vertically adjusting the cutter bar. 90 31. In a mining machine, a support including 105 a horizontally projecting arm, a downwardly extending tubular projection adjacent the free end of the arm, means defining a vertical guideway extending downwardly from the arm behind the tubular projection, a frame below the tubular 110 projection and engaged in said guideway for vertical adjustment therealong, the guideway holding the frame against rotation about a vertical axis, a tubular member telescoped in said projection and having its lower end journaled in said 115 frame, a cutter bar in connection with the lower end of said tubular member and rotatable therewith, means for connecting the cutter bar and frame to hold the cutter bar against movement about the axis of said tubular member, means 120 for driving the cutter bar, and means for vertically adjusting the cutter bar, said driving means including an extensible torque shaft within said tubular projection and member. 32. In a mining machine, a support including 125 a horizontally projecting arm, a downwardly extending tubular projection adjacent the free end of the arm, means defining a vertical guideway extending downwardly from the arm behind the tubular projection, a frame below the tubular 130 projection and engaged in said guideway for vertical adjustment therealong, the guideway holding the frame against rotation about a vertical axis, a tubular member telescoped in said projection and having its lower end journaled in said 135 frame, a cutter bar in connection with the lower end of said tubular member and rotatable therewith, means for connecting the cutter bar and frame to hold the cutter bar against movement about the axis of said tubular member, means for driving the cutter bar, and means for vertically adjusting the cutter bar, said adjusting means including screw and nut within said tubular projection and member. 33. In a mining machine, a support including 140 a horizontally projecting arm, a downwardly extending tubular projection adjacent the free end of the arm, means defining a vertical guideway extending downwardly from the arm behind the tubular 145 projection, a frame below the tubular 150

projection and engaged in said guideway for vertical adjustment therewith, the guideway holding the frame against rotation about a vertical axis, a tubular member telescoped in said projection and having its lower end journaled in said frame, a cutter bar in connection with the lower end of said tubular member and rotatable therewith, means for connecting the cutter bar and frame to hold the cutter bar against movement about the axis of said tubular member, means for driving the cutter bar, means for vertically adjusting the cutter bar, said driving means including a telescoping torque shaft within said tubular projection and member and said adjusting means including a screw housed in a portion of said torque shaft and in threaded engagement with another portion thereof.

34. In a machine of the class described, the combination with a supporting frame, of a cutter bar bodily adjustable relative thereto, a cutter chain circulatory on said cutter bar, an extensible torque shaft comprising telescoping sections for driving said cutter chain in all adjusted positions of the cutter bar, driving means for the torque shaft, a screw and nut concentric with the torque shaft for adjusting the cutter bar relative to the support, means for effecting relative rotation of the screw and nut, the screw being extrinsic to the torque action of the torque shaft, and means operative to hold the cutter bar against swinging about the axis of said torque shaft in all adjusted positions of the cutter bar while permitting free adjustment of the cutter bar.

35. In a machine of the class described, the combination with a supporting frame, of a cutter bar bodily adjustable relative thereto, a cutter chain circulatory on said cutter bar, an extensible torque shaft comprising telescoping sections for driving said cutter chain in all adjusted positions of the cutter bar, driving means for the torque shaft, a screw and nut concentric with the torque shaft for adjusting the cutter bar relative to the support, means for effecting relative rotation of the screw and nut, the screw being extrinsic to the torque action of the torque shaft, and means operative to hold the cutter bar against swinging about the axis of said torque shaft in all adjusted positions of the cutter bar

while permitting free adjustment of the cutter bar, said last named means comprising a guideway on the supporting frame parallel to said torque shaft and means on the cutter bar slidably engaging said guideway.

36. In a machine of the class described, the combination with a supporting frame, of a kerf cutter bodily adjustable relative thereto, said kerf cutter comprising an elongated cutter bar and an endless chain cutter adapted to travel on the periphery of said bar, an extensible torque shaft comprising telescoping sections for driving said kerf cutter in all of its adjusted positions, driving means for the torque shaft, a screw and nut concentric with the torque shaft and connecting said supporting frame and cutter bar for adjusting the kerf cutter relative to said frame, and means for effecting relative rotation of the screw and nut, the screw being extrinsic to the torque action of the torque shaft.

37. In a machine of the class described, the combination with a supporting frame, of a kerf cutter bodily adjustable relative thereto, said kerf cutter comprising an elongated cutter bar and an endless chain cutter adapted to travel on the periphery of said bar, an extensible torque shaft comprising telescoping sections for driving said kerf cutter in all of its adjusted positions, driving means for the torque shaft, a screw and nut concentric with the torque shaft and connecting said supporting frame and cutter bar for adjusting the kerf cutter relative to said frame, and means for rotating the nut relative to the screw, the screw being extrinsic to the torque action of the torque shaft.

38. In a mining machine, a portable frame, a motor carried by said frame, a kerf cutter supported by said frame, power transmission means between said motor and said kerf cutter comprising horizontally spaced sprockets arranged on vertical axes at the top of said frame and an endless chain engaging said sprockets, and controllable means driven through said chain for adjusting said kerf cutter relative to said frame into different planes parallel to each other.
